UNITED STATES PATENT OFFICE

2,052,915

SWING

Henry B. Benningfield, East Peoria, Ill.

Application February 25, 1936, Serial No. 65,678

1 Claim. (Cl. 155—63)

The present invention relates to new and useful improvements in swings for use by children and adults on porches, in amusement parks, etc., and has for one of its important objects to provide, in a manner as hereinafter set forth, a swing embodying novel means through the medium of which said swing may be conveniently operated and controlled with a minimum of effort by the occupants thereof.

10 Other objects of the invention are to provide a swing of the aforementioned character which will be simple in construction, strong, durable, safe, attractive in appearance and which may be manufactured at low cost.

15 All of the foregoing and still further objects and advantages of the invention will become apparent from a study of the following specification, taken in connection with the accompanying drawings wherein like characters of reference designate corresponding parts throughout the several views, and wherein:—

Figure 1 is a view in side elevation of an embodiment of the invention with portions thereof broken away in section.

25 Figure 2 is a view in side elevation of a slightly modified form of the invention with portions thereof broken away in section.

Figure 3 is a top plan view.

Figure 4 is a view in vertical longitudinal section, taken substantially on the line 4—4 of Figure 3.

Figure 5 is a front elevational view.

Figure 6 is a detail view in elevation of the rear hanger.

35 Referring now to the drawings in detail, it will be seen that the reference numeral 1 designates generally a body of suitable dimensions and material the upper portion 2 of which is provided with openings 3 for the entrance of the occupants.

40 Front and rear seats 4 and 5, respectively, are provided in the body for the accommodation of the occupants, said seats including backs 6. The lower portions of the ends of the body 1 are inclined in a manner to provide foot boards 7. The 45 reference numeral 8 designates a foot rail (see Figure 4) which is mounted transversely on the bottom 9 of the body 1 forwardly of the rear seat 5.

The forward end of the body 1 is pivotally

suspended between a pair of supporting levers 10 between which a handle bar 11 extends at an intermediate point. Projecting from the rear end of the body 1 is a pair of brackets 12 to the free end portions of which a substantially U-shaped hanger 13 is pivotally connected. Chains 14 are connected to the levers 10 and the hanger 13 for suspending the swing from a suitable support. Of course, ropes or cables may be substituted for the chains 14.

10 In use, the occupants enter the body 1 and sit on the seats 4 and 5. Then, by grasping the handle bar 11 and pushing and pulling thereon the occupant or occupants of the front seat 4 may operate and control the swing in a manner 15 which is thought to be obvious.

In the modification illustrated by Figure 2 of the drawings, the seats 4 and 5 are reversed relative to each other. In this arrangement the levers 10 and the handle bars 11 are provided at 20 both ends of the body 1 in order that the occupants of both of the seats 4 and 5 may operate and control the swing.

25 It is believed that the many advantages of a swing constructed in accordance with the present invention will be readily understood and although preferred embodiments of the device are as illustrated and described, it is to be understood that further modifications and changes in details of construction may be resorted to which 30 will fall within the scope of the invention as claimed.

What is claimed is:—

A swing of the class described comprising a body including inclined end walls provided foot 35 boards, said body further including a top portion having entrance openings therein, relatively reversed seats mounted in the body, pairs of levers pivotally connected to the end portions of the body on opposite sides thereof, handle bars extending between intermediate portions of the levers constituting said pairs, and flexible elements connected to the levers for suspending the body on a support, said levers and the handle bars constituting means operable from the seats 40 for actuating and controlling the swing.

HENRY B. BENNINGFIELD.
